UNITED STATES PATENT OFFICE

147,773

DESIGN FOR A COMBINATION KITCHEN UTENSIL TOOL

Helena Wolf, Hayward, Calif.

Application April 26, 1946, Serial No. 128,998

Term of patent 14 years

(Cl. D44—29)

To all whom it may concern:

Be it known that I, Helena Wolf, a citizen of the United States, residing at 21430 Montgomery Ave., Hayward, in the county of Alameda and State of California, have invented a new, original, and ornamental Design for a Combination Kitchen Utensil Tool, of which the following is a specification, reference being had to the accompanying drawing, forming part thereof.

In the drawing

Fig. 1 is a side elevation of a combination kitchen utensil tool, showing my new design;

Fig. 2 is an edge view of the left-hand side of Fig. 1.

Fig. 3 is an end elevation of the bottom of Fig. 1.

Fig. 4 is an edge view of the right-hand side of Fig. 1.

Fig. 5 is an edge view of the bottom of Fig. 1.
I claim:

The ornamental design for a combination kitchen utensil tool, as shown.

HELENA WOLF.
